United States Patent Office.

JAMES OGDIN, OF PHILADELPHIA, PENNSYLVANIA.

Letters Patent No. 77,755, dated May 12, 1868.

IMPROVEMENT IN OIL-CANS.

The Schedule referred to in these Letters Patent and making part of the same.

TO ALL WHOM IT MAY CONCERN:

Be it known that I, JAMES OGDIN, of Philadelphia, Pennsylvania, have invented a Device for Drawing off Fluids from Vessels; and I do hereby declare the following to be a full, clear, and exact description of the same.

My invention consists of a device constructed, arranged, and applied to a can, substantially as described hereafter; so that, when the vessel is not in use, the contents cannot escape, and when the fluid is drawn off there is no necessity for removing the stopper of the vessel, which is thus especially useful for containing ignitable fluids.

In order to enable others skilled in the art to make and use my invention, I will now proceed to describe its construction and operation, reference being had to the accompanying drawing, which forms a part of this specification, and in which—

Figures 1 and 2 represent my invention applied to a can for containing fluids.

A represents the body of the can, the upper tapering portion *a* of which is surmounted with a flanged mouth, *b*, for receiving a cork or other suitable stopper, *d*.

To the exterior of the can, at any convenient point, is soldered, or otherwise secured, a socket, *B*, for receiving a tapering plug, *D*, to the upper end of which is secured the spout *E*, the interior of the spout, when the latter is in the position seen in fig. 1, communicating through a passage, *e*, in the plug, and passage, *f*, in the socket with the interior of the can. When the spout, however, has been turned to the position shown in fig. 2, the passage *e* has ceased to communicate with the passage *f*, and hence the communication between the can and the spout is closed.

A tube, *G*, extends from an opening or passage, *i*, in the socket *B*, to a point near the mouth of the can, and forms a communication between the interior of the latter and a channel, *m*, in the plug *D*, when the latter is in the position shown in fig. 1, this channel terminating at a point above the socket, so that air can gain access to it, and pass thence through the tube *G* to the interior of the can. On turning the plug, however, to the position shown in fig. 2, the supply of air is cut off from the tube *G*.

When the can is not required for use, or during transportation, the spout and plug are turned to the position seen in fig. 2, so that there can be no escape of the contents. When, however, the fluid has to be drawn off from the can, the spout is turned to the position shown in fig. 1, and the can tilted, its contents flowing freely from the spout without removing the stopper, owing to the vent afforded by the channel *m* and tube *G*.

I claim as my invention, and desire to secure by Letters Patent—

The combination and arrangement of a can, *A*, pipe *G*, socket *B*, having openings *f* and *i*, and a plug, *D*, fitting the said socket, and having passages *e* *m*, and a spout, *E*, all substantially as described.

In testimony whereof, I have signed my name to this specification in the presence of two subscribing witnesses.

JAMES OGDIN,

Witnesses:

H. HOWSON,

W. J. R. DELANY.
